UNITED STATES PATENT OFFICE.

JESSE G. KING, OF DAYTON, OHIO, ASSIGNOR TO DELCO-LIGHT COMPANY, OF DAYTON, OHIO, A CORPORATION OF DELAWARE.

REFRIGERATING APPARATUS.

Application filed May 30, 1923. Serial No. 642,367.

To all whom it may concern:

Be it known that I, JESSE G. KING, a citizen of the United States of America, residing at Dayton, county of Montgomery, and State of Ohio, have invented certain new and useful Improvements in Refrigerating Apparatus, of which the following is a full clear, and exact description.

This invention relates to refrigerating apparatus, and more particularly to refrigerating machines for domestic use in which a cooling unit such as an evaporator and brine tank associated therewith, is supported within a refrigerator cabinet.

It is among the objects of the present invention to so support the cooling unit that, during transportation of the refrigerator, the liability of damage will be reduced to the minimum.

Other and further objects of the present invention will be apparent from the following description reference being had to the accompanying drawings wherein a preferred embodiment of one form of the present invention is clearly shown.

In the drawings:

Fig. 1 is a side elevation of a refrigerator cabinet, a portion thereof being shown in section to show the cooling unit and support therefor constructed in accordance with the present invention;

Fig. 2 is a view on the line 2—2 of Fig. 1, showing the front elevation of the cooling unit and showing in section a portion of the refrigerator cabinet;

Fig. 3 is a view similar to Fig. 2 showing a modified form of the invention; and

Fig. 4 is a side elevation of the apparatus shown in Fig. 3, looking in the direction of the arrow 4 of Fig. 3.

The present invention comprises chiefly a bracket for supporting a refrigerator cooling unit within a refrigerator cabinet, said bracket having a relatively movable portion yieldingly maintained against the cooling unit by spring pressure. This construction permits the cooling unit to move slightly relative to the bracket in order partially to absorb the shock to which the walls of the unit are subjected, particularly when, during transportation, brine in the cooling unit is agitated.

In the drawings, 20 designates a refrigerator cabinet including the cooling compartment 21 provided with a door 22. The cool-

ing chamber 21 is provided with a metal lining 23 surrounded by insulating material 24 or the like which is spaced from the outer walls 25 and 26 of the cabinet to provide a dead air space for insulating purposes.

The cooling unit includes a brine tank 30 adapted to receive one or more ice trays 31 which are removable from a space extending within the brine tank. Brine tank 30 encloses and supports an evaporating chamber 32 connected by pipes 33 and 34 with refrigerating mechanism not shown. This mechanism may be located within the refrigerator cabinet below the food compartment if desired. A plurality of pipe loops 35 are connected with the evaporator chamber 32 for circulating refrigerant gas through the brine in the tank 30.

The brackets for supporting the cooling unit shown in Figs. 1 and 2 each comprises a U-shaped member 40 which extends along the side and bottom walls of the brine tank 30, and a relatively movable bar 41 which extends across the top of the cooling unit and is yieldingly pressed against the top of the brine tank 30 by means of springs 42 which bear against the lining 23 and the movable bar 41. The bracket members 40 are suspended by means of bolts 43 and nuts 44 from channel-shaped supporting members 45 located above the cooling unit and in the air space between the refrigerator top wall 26 and the insulating material 24. These channels 45 are supported at their ends upon ledges 46 and 47 secured to the outer walls of the cabinet. The spacing of the bracket member 40 from the channels 45 is determined by sleeves 48 which extend through the insulating material 24 and the lining 23, and loosely through the apertures in the ends of the bar 41.

During transportation of the refrigerator with the cooling unit containing brine assembled therein the splashing of the brine within the tank 30 against the interior of the walls of the brine tank will subject the cooling unit to considerable vibration which might disrupt or permanently deform the walls of the cooling unit unless the unit were supported in such a manner that it could change its position slightly by bodily movement thereof. Since the bracket is provided with a relatively movable portion resiliently pressed against the top wall of the unit the cooling unit may move slightly in a vertical

direction and thereby relieve its walls of severe vibration due to the splashing of the brine within the brine tank.

In the form of the invention shown in Fig. 3 the brine tank 30^a is provided at its upper end with the evaporator chamber 32. The tank 30^a is suspended within a plurality of U-shaped brackets 50 connected by rods 53 of resilient material, each provided with a bent portion 54 adapted to bear against the surface of the brine tank adjacent the evaporator chamber 32. By reason of the resiliency of the bars 53 the cooling unit is permitted to move slightly within the U-shaped frame members 50 in order to relieve the walls of the brine tank of severe vibration during the splashing of the brine therein. The U-shaped members 50 are suspended from channel members 45 by means of bolts and nuts 55 and 56.

The refrigerator cooling compartment is usually provided with cover 58 having openings 59 through which the ice trays 31 or 31^a may be withdrawn. In Figs. 3 and 4, in order that the ice tray openings in the brine tank can be arranged to register with openings 59, there is enough clearance provided between the brine tank 30^a and the U-shaped brackets 50 so that the brine tank can be shifted sideways. The bars 53 are provided with adjustable clamping nuts 60 for holding said rod 53 in any adjusted position with respect to the brine tank support. After the brine tank 30^a is located in the correct position, the bars 53 are clamped with respect thereto and will hold same in this position. The brine tank support can be raised or lowered for the purpose of vertically arranging the brine tank 30^a with respect to the openings 59 in the cover 58 by providing washers 61 which can be inserted or withdrawn from between the U-shaped bracket 50 and lining 23.

While the form of mechanism herein shown and described constitutes a preferred embodiment of one form of the invention it is to be understood that other forms might be adopted and various changes and alterations made in the shape, size, and proportion of the elements without departing from the spirit and scope of the invention.

What is claimed is as follows:

1. Refrigerating apparatus comprising the combination with a cabinet having a cooling compartment; of a cooling unit; and means for supporting the cooling unit within the cabinet comprising a bracket supported by the cabinet within the cooling chamber and adapted to support the cooling unit, said bracket including a relatively movable por-

tion resiliently engaging a portion of the cooling unit.

2. Refrigerating apparatus comprising the combination with a cabinet having a cooling compartment; of a cooling unit adapted to be located within the compartment; a bracket supported by the cabinet within the cooling chamber and including a substantially U-shaped portion for receiving the cooling unit and a bar resiliently engaging the cooling unit to permit movement of the cooling unit relative to the U-shaped portion.

3. Refrigerating apparatus comprising the combination with a cabinet having a cooling compartment; of a cooling unit adapted to be located within the compartment; a U-shaped bracket supported by the cabinet within the cooling chamber and extending adjacent the side and bottom walls of the cooling unit; and a bar resiliently bearing against the top wall of the cooling unit to permit movement of the cooling unit relative to the bracket member.

4. Refrigerating apparatus comprising the combination with a cabinet having a cooling compartment; of a cooling unit adapted to be located within the compartment; a U-shaped bracket supported by the cabinet within the cooling chamber and extending adjacent the side and bottom walls of the cooling unit; and a rod of resilient material having its ends attached to the U-shaped bracket, and having an intermediate portion bearing against the top wall of the cooling unit.

5. Refrigerating apparatus comprising the combination with a cabinet including a lining of insulating material and outer walls spaced from said lining; of a cooling unit adapted to be supported within the cabinet; and means supported by the outer walls of the cabinet and located within the lining and adapted to receive the cooling unit and having provisions permitting movement of the cooling unit relative to the cabinet.

6. Refrigerating apparatus comprising the combination with a cabinet having a cooling compartment; of a cover for said compartment and having an opening therein; of a cooling unit adapted to be located within the compartment and having an opening adapted to be arranged to register with the opening in said cover; of a support for said cooling unit, said support comprising means for resiliently securing the cooling unit in position with respect to said cover.

In testimony whereof I hereto affix my signature.

JESSE G. KING.
